UNITED STATES PATENT OFFICE.

LEONARD C. ASCH, OF NEW YORK, N. Y.

DESIGN FOR A HAND BAG OR THE LIKE.

Application filed February 9, 1925. Serial No. 12,313. Term of patent 3½ years.

To all whom it may concern:

Be it known that I, LEONARD C. ASCH, a citizen of the United States of America, residing in the city, county, and State of New York, have invented a new, original, and ornamental Design for Hand Bag or the like, of which the following is a specification, reference being had to the accompanying drawing, forming a part thereof.

In the drawing,

I claim:

The ornamental design for a hand bag or the like substantially as shown.

LEONARD C. ASCH.
